AXMINSTER TUBE FRAME SUPPORT
MECHANISMWellesley B. Cooper, Amsterdam, N. Y., assignor
to Bigelow-Sanford Carpet Co. Inc., Thomps-
onville, Conn., a corporation of Massachu-
sets

Application July 14, 1936, Serial No. 90,524

6 Claims. (Cl. 139—7)

This invention relates to pile fabric looms of the Axminster type in which the pile yarn is conveyed to the loom by means of tube frames, carried by a movable chain carrier, and particularly 5 to a novel mechanism adapted to relieve the chain carrier of the weight of the protruding tube frames when the course of the chain departs from the horizontal.

In the usual Axminster loom, the tube frames 10 are so designed and so mounted in the links of the chain carrier that the center of gravity of the tube frame is on one side of the chain, with the result that when the course of the chain carrier departs from the horizontal, the weight of the 15 tube frame, which is substantial, exerts a rotational twisting strain on the links of the chain, or the tube frame brackets connecting the tube frames with the chain, or both, which has resulted in frequent breakage of those parts.

20 The object of the present invention is to relieve the parts of these strains and I have found that that result may be accomplished by the provision of a number of supporting fingers, each adapted to abut a portion of the under surface 25 of the tube frame and to support the weight thereof. As will appear, the supporting fingers which I provide for the purpose, are preferably mounted on an auxiliary chain adapted to run closely adjacent to the course of the chain carrier, and at 30 the same rate of speed therewith, so that the abutting, supporting position of the fingers beneath the tube frames is maintained during feed of the chain carrier.

These and further objects and advantages of 35 my invention will appear from a more detailed description thereof taken in connection with the accompanying drawings, in which:

Fig. 1 is an elevation view of a chain carrier with tube frames, shown as rounding a sprocket to 40 indicate the manner of presenting and maintaining my novel supporting fingers in their proper position relative to the tube frames to be supported;

Fig. 2 is a sectional elevation view on the line 2—2 of Fig. 1;

Fig. 3 is a detail perspective view indicating the mode of operation of my novel supporting fingers, in which view the tubes and the usual 50 bracket with which the tube frame is mounted in the chain carrier have been omitted for clearness;

Fig. 4 is a detail perspective view of a tube frame carrier chain and sprocket, and

Fig. 5 is a detail sectional view taken on the

line 5—5 of Fig. 1, indicating the manner of securing a tube frame in a carrier chain.

Referring to Fig. 1 of the drawings, 1 indicates one of the two chains of a chain carrier, of usual sort, employed for conveying tube frames 3 into 5 position in proximity to the weaving point in an Axminster loom. The chain 1 may, as is customary, be constructed of series of double links 5 and 7, (Fig. 4) connected by single links 9. The sprocket 13, over which the chain 1 is 10 trained, is of the usual type having pairs of ears 15 and 17 disposed at suitable intervals around its periphery, each pair being adapted to straddle a single link 9 of the chain to advance the chain by abutment with links 5 and 7. The chain 15 carrier mechanism includes two chains 1, one on each end of the tube frame, as is well known, and there would be two sprockets 13 to advance these chains at equal rates of speed, as indicated in Fig. 2. 20

The opposite ends of the tube frames 3 are supported in the chains 1 by brackets 11 received within the spaces between the double links 5 and 7 of the chains. The particular manner of securing the brackets to the chains is immaterial 25 so far as my invention is concerned, and it may be in such a way that the tube frames are adapted to be removed bodily from the chain carrier and presented to the weaving point and returned by suitable transferring mechanism, or so that 30 the tube frames are kept in the chains during the weaving and the yarn carried from the tube frames to the weaving point by nippers, as in the customary nipper type of loom. As typifying any suitable mechanism of this character, I 35 have indicated the bracket 11 in Fig. 5 as having an arm 12 received by the links 5 and 7 of the chain, an arm 19 secured to the spool 22 and an arm 23 supporting the tubes 25. The end of arm 12 of the bracket is received between the 40 links 5 and 7 of the chain and a spring latch 24 temporarily holds the tube frame in the chain. The bracket on the opposite end of the tube frame is, of course, similarly constructed and supported.

Chain carriers of the type above described are 45 usually provided above the loom with a number of long horizontal courses, one above another, in which the tube frames are stored, and the chains pass from one course to another around sprockets. As the lowermost course of the carrier approaches 50 a position above the weaving point, it turns vertically to bring the tube frames into position to be accessible by the transferring mechanism or nippers, depending upon the style of loom.

As indicated in Fig. 1, the center of gravity of 55

the tube frame is well outside of the chain and it is obvious that as the chain moves out of the horizontal, such as when it rounds a sprocket, the weight of the tube frame tends to rotate the frame about the chain to twist and break the chain links or brackets.

To relieve the carrier and brackets of this strain, I provide, for each tube frame, one or more supporting fingers 20 adapted to bear 10 against any suitable portion or portions of the under surface of the tube frame, such, for example, as the flange 21 of the spool (Fig. 5).

In accordance with the preferred embodiment of my invention the supporting fingers are presented to their supporting positions indicated only 15 when the course of the carrier 1 departs from the horizontal. As this supporting position relative to the advancing tube frames must be maintained during advance of the carrier, I further provide 20 that the supporting fingers are advanced at a rate of speed equal to that of the carrier.

To that end, the fingers 20 are mounted on an auxiliary chain 26 to project therefrom in the manner indicated and the chain 26 is trained over 25 an auxiliary sprocket 27 closely adjacent the sprocket 13 and preferably of about the same diameter as the latter. An idler sprocket 28 may be provided to take the slack of the auxiliary chain.

30 The construction of the auxiliary chain 26 is similar to that of the chain carrier 1 and as indicated in detail in Fig. 3, the chain 26 has series of paired links 31 and 32 connected by single links 33. The sprocket 27 has opposed ears 35 and 37 35 which straddle the single links 33 to propel the chain as in the chain carrier 1. The sprocket 27 may be secured on the shaft 39 to which the sprocket 13 is secured, or any other suitable means may be provided for rotating the companion sprockets at the same rate of speed.

30 Protruding from the outer edge of each of the single links 33 of the chain 26 is the aforesaid supporting finger 20 which is preferably formed as an integral part of the link 33.

45 The proper spacing of the fingers 20, relative to that of the tube frames, may conveniently be obtained by making the links of the finger-carrying chains of the same dimensions as the links of the tube frame carrier chains 1. Any suitable provision may be made to insure that the supporting surfaces of the fingers 20 come into 50 alignment with the flanges 21 of the spools or other portions which they are to abut, and, as indicated in Figs. 2 and 3, I may effect this result by mounting the sprocket 27 on the inside of 55 the sprocket 13 and providing each supporting finger 20 with a reverse bend 41 whereby to bring the supporting surfaces of the fingers in the desired alignment with the flanges of the spool.

60 Preferably a similar set of fingers 20 with chain 26 is provided adjacent the opposite carrier chain 1 to support that end of the tube frames as indicated in Fig. 2.

With the device constructed as above described, 65 the supporting fingers 20 are gradually presented to the tube frames as the course of the carrier approaches an inclination to the horizontal and the desired supporting and abutting relationship between the tube frames and fingers is preserved 70 as the carrier passes around the sprocket and returns to its horizontal position indicated at the bottom of Fig. 1, after which the fingers 20 are withdrawn from their supporting position.

75 My invention is not to be limited to the use of such supporting fingers during the travel of the

tube frame carrier around a sprocket, as I have described that construction merely for the purpose of illustrating one good form of my invention. Obviously, a similar arrangement can be provided to insure support during any course of 5 the carrier chain which is out of the horizontal by simply extending the adjacent course of the auxiliary chain 25 as by using additional auxiliary sprockets.

I claim:

1. A pile fabric loom tube frame supporting mechanism, for use with a movable chain carrier conveying a plurality of tube frames and having means guiding the course of travel of the chain carrier out of the horizontal, comprising the combination of auxiliary chain means having spaced fingers projecting therefrom at intervals approximating the spacing of the tube frames in said carrier, means guiding the auxiliary chain means along a path adjacent the carrier to dispose the said fingers in position to support the weight of the tube frames when the course of travel of the carrier departs from the horizontal, and mechanism adapted to feed the auxiliary chain means in said path at substantially the same 25 rate of speed as that of the carrier to maintain the said supporting position during the non-horizontal course of the carrier.

2. A pile fabric loom tube frame supporting mechanism for use with a movable chain carrier 30 conveying a plurality of tube frames, comprising the combination of a plurality of tube frame supporting fingers, a movable support for the fingers on which the fingers are mounted in fixed predetermined position, and means for moving the 35 support, the fingers being projected into tube frame supporting position solely by said movement of the support.

3. A pile fabric loom tube frame supporting mechanism for use with a movable chain carrier 40 conveying a plurality of tube frames and having means guiding the course of travel of the carrier along a straight path which departs from the horizontal, comprising the combination of a plurality of tube frame supporting fingers, a movable support for the fingers on which the fingers are mounted in fixed predetermined position, and means for moving the support to maintain the fingers in tube frame supporting position during the travel of the carrier along said straight-non- 45 horizontal path.

4. A pile fabric loom tube frame supporting mechanism for use with a movable chain carrier conveying a plurality of tube frames and having sprockets guiding the course of travel of the 55 carrier out of the horizontal, comprising the combination of a plurality of tube frame supporting fingers, a movable support for the fingers on which the fingers are mounted in fixed predetermined position and means guiding said support along a predetermined path to position said fingers in the path of said tube frames wholly by movement of the fingers in a plane normal to the axis of said sprockets.

5. A pile fabric loom tube frame supporting 65 mechanism for use with a movable chain carrier conveying a plurality of tube frames and having means guiding the course of travel of the chain carrier out of the horizontal, comprising the combination of auxiliary chain means, 70 sprockets guiding the auxiliary chain means along a course adjacent the said chain carrier, spaced tube frame supporting fingers secured to said auxiliary chain means and projecting outwardly therefrom in directions to protrude radially as 75

the auxiliary chain means passes around a sprocket and means feeding the auxiliary chain means at substantially the same rate of speed as the carrier to maintain the fingers in said 5 supporting position during the non-horizontal course of the carrier.

6. A pile fabric loom tube frame supporting mechanism for use with a movable chain carrier conveying a plurality of tube frames and having 10 means guiding the course of travel of the chain carrier out of the horizontal, comprising the combination of auxiliary chain means, sprockets guid-

ing the auxiliary chain means along a course adjacent the said chain carrier, spaced tube frame supporting fingers mounted in fixed predetermined position on said auxiliary chain means and projecting outwardly a fixed distance therefrom in directions to protrude radially as the auxiliary chain means passes around a sprocket and means feeding the auxiliary chain means at substantially the same rate of speed as the carrier to maintain the fingers in said supporting position during the 10 non-horizontal course of the carrier. 5
